UNITED STATES PATENT OFFICE

133,059

DESIGN FOR A MUSICAL SIGNAL DEVICE OR SIMILAR ARTICLE

Alexis C. Grohsgal, New York, N. Y., assignor to Marks Products Co. Inc., Brooklyn, N. Y., a corporation of New York

Application January 24, 1941, Serial No. 98,354

Term of patent 14 years

To all whom it may concern:

Be it known that I, Alexis C. Grohsgal, a subject of the former Tsar of Russia, and a resident of New York city, in the county of New York, State of New York, have invented a new, original, and ornamental Design for a Musical Signal Device or Similar Article, of which the following is a specification, reference being had to the accompanying drawing, forming part thereof.

The figure is a perspective view of a musical signal device or similar article showing my new design.

I claim:

The ornamental design for a musical signal device or similar article, substantially as shown.

ALEXIS C. GROHSGAL.
